(57) **CLAIM**

The ornamental design for a wireless repeater, as shown and described.

DESCRIPTION

FIG. 1 is a front and left side perspective view of a wireless repeater showing our new design with features illustrated in broken lines for illustrative purposes and thus not constituting a part of the claimed design

FIG. 2 is a back and right perspective view thereof;

FIG. 3 is a left side elevation view thereof;

FIG. 4 is a right side elevation view thereof;

FIG. 5 is a front elevation view thereof;

FIG. 6 is a back plan view thereof;

FIG. 7 is a bottom elevation view thereof; and,

FIG. 8 is a top elevation view thereof.

The dashed lines in the drawings are environmental and for illustrative purposes only and form no part of the claimed design. The dot-dash lines illustrate boundaries and form no part of the claimed design.
